UNITED STATES PATENT OFFICE.

CHARLES B. SCHREPEL, OF COATS, KANSAS.

TWINE-TENSION FOR BINDERS.

No. 866,738.

Specification of Letters Patent.

Patented Sept. 24, 1907.

Application filed December 29, 1906. Serial No. 349,954.

To all whom it may concern:

Be it known that I, CHARLES B. SCHREPEL, a citizen of the United States, residing at Coats, in the county of Pratt and State of Kansas, have invented certain new and useful Improvements in Twine-Tensions for Binders, of which the following is a specification.

This invention relates to twine tensions for binders of that class wherein the twine is maintained at a substantially uniform tension between the needle and the knoter irrespective of the position of the needle and which avoids the imposition of strain on the twine at all points between such device and the twine box, and my object is to produce a tension device of this character which will operate efficiently and reliably and embodies the desirable features of simplicity, strength, durability and cheapness of construction.

With this and other objects in view the invention consists in certain novel and peculiar features of construction and organization as hereinafter described and claimed; and in order that it may be fully understood reference is to be had to the accompanying drawing, in which—

Figure 1, is a side view of a binder needle equipped with a tension device embodying my invention. Fig. 2, is a section on the line II—II of Fig. 1. Fig. 3, is a fragmentary view taken on the line III—III of Fig. 2. Fig. 4, is a fragmentary view taken on the line IV—IV of Fig. 1. Fig. 5, is a side view on a reduced scale of a corn binder needle equipped with a tension device embodying the invention. Fig. 6, is a fragmentary sectional perspective view taken approximately on the line VI of Fig. 5.

In the said drawing, 1 indicates a needle of the usual configuration in side view but reduced in thickness as shown so that its shank 2 and its heel portion shall be formed with connecting ribs 3 and 4 respectively. The shank of the needle is provided with the usual opening 5 whereby it is mounted on the operating shaft, not shown, and contiguous to said opening is a guide hole 6, which by preference is formed in the reduced portion 3 of the shank. The needle is also provided in said reduced portion at the junction of the shank and the lower portion with a substantially boot-shaped opening, comprising the leg portion 7, and the foot portion 8, the latter extending substantially longitudinally of the shank, which at the inner end of the opening is grooved as at 9, to permit the twine T to enter said foot portion of the opening with the least deflection or bending possible.

10 indicates a guide forming a part of the reduced portion of the needle and projecting into the boot-shaped opening 7 and terminating in outwardly projecting horns 11 flanking the shallow channel 12 in the outer end of the lug, such channel being in line with the passage 13 leading to flaring eye 14 at the front end of the needle. To reduce wear on the face of said

channel and the lower portion of the eye due to the friction of the twine thereon, I provide a hard metal spring plate 15 engaging the base of the channel and terminating in a hook 16 snugly embracing the lower portion of the eye, said wear plate, as it is in fact, being secured in position preferably by means of a screw bolt 17 extending through the lower end of the wear plate and into the needle as shown clearly in Fig. 3. At the lower margin of the boot-shaped opening 65 the reduced portion of the needle is widened at each side by ribs 18, and below said ribs is provided with apertures 19, the series being arranged longitudinally of the lower portion of the needle.

20 indicates a pair of flat springs fitting against the lower portion of the needle and having their upper ends fitting snugly together as lips 21 within the leg portion of the boot shaped opening, the intermediate portions of the springs being oppositely bowed as at 22, so as to provide the necessary stiffness and to fit 75 around the ribs 18 hereinbefore described, the bowed portions of the springs being provided with openings 23, through which the horns 11 project, and by which the springs are guided in their movement. The springs thus arranged form closures for the opening which 80 absolutely guard against lateral slippage of the twine from the horns.

The springs are secured reliably to the reduced portion 4 of the needle by bolt 24 and above said bolt are provided with longitudinal series of apertures 25 registering with apertures 19 of the needle and through one or another of said series of aligned apertures a clamping bolt 26 extends and is engaged at its threaded end by a nut 27. By causing the clamping bolt to engage different sets of holes or apertures, a variation of the 90 pressure of the lips on the twine is effected.

The twine extends from the twine box, not shown, through the guide hole 6, then alongside the reduced portion 3 of the stem and through the groove 9 in the corresponding side of the needle and into the foot portion of the boot shaped opening. From said point the twine extends up through the horned guide 10 in the channel 12 thereof, between the lips of the clamp element of the device and then up through passage 13 and inwardly through the eye 14 to the knoter, 100 not shown.

The twine is adapted for engagement with the grain at a point between the tip of the needle and the knoter in the usual manner, so that upon the upward movement of the needle, the bundle may be encircled by 105 the twine and the latter then tied in the usual manner. As the twine is drawn through the needle, the spring pressed lips yield and reclamp the twine the instant its feeding movement ceases. It will be understood that between the clamping point and the knoter, the 110 twine makes only a single bend, viz. where it passes through the eye 14 and that at the other bending point

namely at the lower corner of the horned guide and at the hole 6, no tension is imposed upon it, it being of course understood that no tension is imposed upon the twine at any point between the guide hole 6 and the 5 twine box.

As a result of this fact it is apparent that there is no appreciable wear by the twine on the needle or any other part except in the passage 13 of the eye of the needle, at which points the wear plate protects the 10 needle, said plate being removable in order that it may be replaced with a new one when desirable.

The twine is under tension from the point of the needle to the twine tension device in any construction where the tension is located back of or extraneous of 15 the needle and consequently there is an appreciable wear upon the needle due to the frictional action thereagainst of the twine and this is true particularly at all points where the twine is bent. It will furthermore be apparent that in such types of construction the 20 deepening of the guides caused by the friction of the twine results in the imposition on the twine of variable pulling strains due to the fact that the enlargements of the twine bind more tightly in such portions of the guideways than the smaller portions of the twine. 25 With my invention, the only variation in the tension will occur when a thickened portion of the twine passes between the lips of the clamp, there being no material variation of tension in the passage of such thickened portions through the eye of the needle as 30 the latter will not wear appreciably because protected by the wear plate or otherwise hardened base of passage 13.

In Figs. 5 and 6, which show a needle for corn binders, that portion between the shank and the lower 35 portion of the needle is closed by a web or rib 28 which forms a substitute for the reduced portion of the needle of the other figures. This rib or web is provided by preference with guide loops 29 bridging holes 6 at each side of the needle, it being understood of course that 40 said loops or said hole may be dispensed with or may be used separately or jointly, or, where the web or rib is provided with an eye 30 in the heel of the needle the twine may lead from said eye through hole 6 or loop 29, as desired and thence to the horned guide. It will 45 be understood of course that with either type of needle the twine will extend through hole 6 from the side opposite from the groove 9 through which it passes into the boot-shaped opening.

From the above description it will be apparent that 50 I have produced a twine tension for binders possessing the features of advantage enumerated as desirable and I wish it to be understood that I do not desire to be

restricted to the exact details of construction shown and described as obvious modifications will suggest themselves to one skilled in the art. 55

Having thus described the invention what I claim as new and desire to secure by Letters Patent is:-

1. The combination of a needle provided with a passage and an eye and guide and with a transverse opening between the guide and passage, and a pair of lips projecting into said opening from opposite sides of the needle and pressed yieldingly together. 60

2. The combination of a needle provided with a passage and an eye and a guide and a pair of springs secured to the needle and disposed at opposite sides of said guide and provided with lips pressed yieldingly together between said guide and passage. 65

3. The combination of a needle provided with a passage and an eye and opening, a guide in said opening, horns projecting laterally therefrom, and a pair of springs secured to the needle and disposed at opposite sides of said guide and provided with openings to receive said horns and with lips pressed yieldingly together in said opening. 70

4. The combination of a needle provided with a guide hole in its shank and with a passage and an eye and opening, a horned guide in said opening, and a pair of spring secured to opposite sides of the needle and provided with openings to receive the horns and with lips pressed yieldingly together in said opening. 75

5. The combination of a needle provided with a guide hole in its shank and with a passage and an eye and a substantially boot-shaped opening, said boot-shaped portion having its foot portion disposed longitudinally of the shank and its leg portion projecting toward the point or eye of the needle, a guide projecting into the boot-shaped opening and provided at its outer end with a channel longitudinally aligned with said passage and with laterally projecting horns at opposite sides of said channel, and a pair of springs secured to the needle at opposite sides of said leg and provided with openings to receive said horns and at their upper ends with lips held yieldingly together in said opening. 80

6. The combination of a needle provided with a passage, an eye and an opening, and also provided with a twine guide in said opening, and springs secured to opposite sides of the needle and terminating in lips projecting into said opening from opposite sides thereof between the guide and passage and adapted to clamp the twine between them; said springs being bowed outwardly between said lips and the points where they are secured to the needle. 85

7. The combination of a needle provided with a passage, an eye and an opening, and also provided with a twine guide in said opening and at the end of the opening most remote from the eye with outwardly projecting ribs, and springs secured to opposite sides of the needle and bowed outwardly around said ribs and terminating in lips projecting from opposite sides into said opening between the guide and passage and adapted to clamp the twine between them at such point. 105

In testimony whereof I affix my signature, in the presence of two witnesses.
